BRASSIÈRE AND BUST GARMENT

Raleigh McCabe, Chicago, Ill.

Application July 6, 1936, Serial No. 88,924

1 Claim. (Cl. 2—42)

This invention relates to improvements in brassières or bust garments.

One of the objects is to provide a brassière of improved form, simplified construction, and reduced cost.

Another object is to provide a garment as described which is form fitting and has features of adjustability.

Another object is to provide a garment as described which is adapted to provide proper support and has combination features of utility.

A further object is to provide a garment having the above mentioned objects and adapted to have various modes of attachment.

Other objects and advantages will be apparent and brought out more fully in the following description, reference being had to the accompanying drawings, wherein:

Fig. 1 is an outer or face view of the garment embodying my invention and showing a neck strap attachment;

Fig. 2 is a view of the inner side of the garment;

Fig. 3 is a partial end sectional view enlarged, taken along the line 3—3 of Fig. 1;

Fig. 4 is a partial cross sectional view through one of the darts, taken along the line 4—4 of Fig. 1;

Figs. 5—8, inclusive, are views illustrating one mode of attachment of the garment;

Figs. 9 and 10 respectively, are similar views showing modified modes of attachment;

Fig. 11 is a view similar to Fig. 1, showing the outer member partially folded back;

Fig. 12 is a sectional view taken substantially along the line 12—12 of Fig. 7;

Fig. 13 is a view of the garment partially completed;

Fig. 14 is a detail view of one of the members forming the outer portion of the garment;

Fig. 15 is a partial sectional view enlarged, taken along the line 15—15 of Fig. 11; and

Fig. 16 is a similar view taken along the line 16—16 of Fig. 1.

Referring more particularly to the drawings and especially to Figs. 11 and 13, I show a garment having an inside member 20 preferably of one piece of material, and an outer member 21 preferably formed with two panels 22. Inner member 20 has side edges 23, a somewhat V-shaped top edge 24, and bottom edge 25. (Fig. 2.)

Inner member 20 is further provided with breast openings 26, the edges of which are turned in and stitched, forming a narrow finished seam 27.

The side edges 23 and the top edge 24 are rein-

forced with a narrow bias edge facing 28 and stitched at 29 and 30. (Fig. 12.) Buttons 31 are shown at the intersection of edges 23 and 24. Panels 22 are each provided with a side edge 32, top edge 33, middle or meeting edge 34, and bottom edge 35. Slits 36 and 37 are cut in each member 22 in edges 32 and 34, respectively, and stitched at 38 forming a French seam and constituting darts 39. Members 22 are sewed together along edge 34 at 40 and form a finished seam, the goods being turned back and given a second stitching at 41. A lining strip 28a is secured along edges 33 and stitched at 29a and 30a (Fig. 12) in a manner similar to finished seam 27 and facing 28. Panels 22, which together form outer member 21, have finished edges 42 stitched at 43, and a bottom stitching 44 secures together the bottom edges of members 20 and 21. Auxiliary finished seam stitching 45 is further provided in member 20 (Fig. 3), which, with stitching 44, defines the bottom edge 46 of the garment adapted to lie along the diaphragm of the body or bust. A plain inside seam 47 is formed by appropriate stitching, the outer ends of which are curved upwardly, defining a somewhat flat diaphragm band. A vertical stitching 48 between the breast openings 26 or along the sternum secures members 20 and 21 together along this line. This stitching, together with the fullness of the panels 21 and the darts 39, forms breast pockets 49 as clearly illustrated in Fig. 12, the lower edges of the pockets 49 being adapted to provide a degree of support for the breasts if desired. Buttonholes 50 are provided in outer member 21 and adapted to cooperate with buttons 31, and a neck strap 51 having buttonholes 52 may be used to support the garment by attachment to buttons 31. At the lower outer corners of the garment buttons 53 are provided for attachment of the garment to a garter band 54.

As a modified mode of attachment of the garment where the garter band may not be used, bands 55 are attached to buttons 53, crossed in the back at 56, and brought around to the front and tied at 57 adjacent the diaphragm. As a further optional mode of attachment, particularly where it may be desired to use the garment as with an evening gown or the like, and the neck strap 51 dispensed with, shoulder straps 58 may be attached to buttons 31 and brought down the back over the shoulder blades and secured in any suitable manner to bands 55 as shown in Fig. 10.

From the foregoing description the various advantages of the garment should be apparent. It will be readily seen that the garment is adapted

to be either a body garment or a brassière and is readily attachable to a garter belt or corset or to an attachable belt by the buttons as described. The garment may be designed to cover the dia-
5 phragm or the diaphragm band may be abbrevi-
ated for hot weather use. As described, the off-
set darts form the breast pockets together with
the sternum stitching 41, and provide ample sup-
port for the breasts and abdomen. As shown in
10 Fig. 12 the inner member 20 fits snugly across the
diaphragm and upper portion of the bust and
serves to position the garment such that no ac-
cidental displacement can occur. The outer
member 21 by forming the individual breast pock-
ets as described, forms them in accordance with
15 the present mode. The breast pockets as de-
scribed are adapted for artificial filling to define
a natural form in such instances as may be de-
sired. The garment, as described, is a suitable
20 foundation for an evening gown, the straps being
removable and may be interchanged with straps
of the same material as the evening gown, the
desirability of which is well recognized.

Thus the garment as described is adapted for
25 greater freedom and comfort as well as a wide
range of utility. The outer panel members 22
are adapted to be independently unbuttoned for
the convenience of nursing mothers.

While I have illustrated and described the pre-
ferred form of construction for carrying my in-
vention into effect, this is capable of variation
and modification without departing from the
spirit of the invention. I, therefore, do not wish 5
to be limited to the precise details of construc-
tion set forth, but desire to avail myself of such
variations and modifications as come within the
scope of the appended claim.

Having thus described my invention, what I 10
claim as new and desire to secure by Letters Pat-
ent is:

A brassière or the like garment as described,
comprising inner and outer members, said inner
member having breast openings whereby said in-
ner member snugly fits the bust at all points, and
said outer member adapted to substantially cover
said inner member and having breast pockets
adapted to support the breasts, said members
being secured together along their lower edges 20
and along a line immediately below the breasts
whereby to form a diaphragm band, said mem-
bers being detachably attached at points at the
top thereof whereby said outer member may be
partially or wholly folded downwardly to expose 25
either or both breasts.

RALEIGH McCABE.
